(57) **CLAIM**

The ornamental design for a pet harness, as shown and described.

DESCRIPTION

FIG. 1 is a perspective view of a pet harness, showing my design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front view thereof; and,

FIG. 7 is a rear view thereof.

The broken lines in FIGS. 1 through 7 illustrate portions of the pet harness that form no part of the claimed design.
